CLAIM

The ornamental design for a mesh netting foundation for a hairpiece, as shown and described.

DESCRIPTION

FIG. 1 is a perspective view of a mesh netting foundation for a hairpiece showing my new design;

FIG. 2 is a bottom view thereof with hair attached to the foundation;

FIG. 3 is a top view thereof with hair attached to the foundation;

FIG. 4 is a front side view thereof;

FIG. 5 is a rear side view thereof;

FIG. 6 is a right side view thereof;

FIG. 7 is a left side view thereof;

FIG. 8 is a perspective view thereof shown in use; and,

FIG. 9 is another perspective view thereof shown in use—with hair attached to the top of the foundation.

The broken lines showing hair within FIG. 2 and FIG. 3 of the drawing disclosure, the broken line outline of the partial human figure in FIG. 8, and the broken line outline of the partial human figure and hair on top of the mesh netting foundation in FIG. 9 assist in illustrating how the mesh netting foundation for a hairpiece may appear when in a position of use, but form no part of the claimed design.
